SLAT LINK

Kurt T. Kiefer, Chicago, Ill., assignor to Kurdon, Inc., Chicago, Ill., a corporation of Illinois

Application June 14, 1954, Serial No. 436,429

3 Claims. (Cl. 160—173)

This invention relates to a new and improved slat link for vertical slat Venetian blinds. The link improves the operation of substantially free-hanging slats and mainly the slat-separating the slat-gathering movements required from time to time.

Various attempts have been made in the past to construct Venetian blinds with vertical, free-hanging slats, it being clear that such an installation is desirable because of its basic simplicity of manufacture and use and because a more perfect seal can be formed between freely hanging vertical slat edges than by any other Venetian blind mechanism. However difficulties were encountered. For instance the slats tended to swing in the wind and to become damaged as a result; or when they were somehow restrained from such swinging it became difficult to separate and gather them rapidly and smoothly.

It is a basic object and feature of the present invention to provide a slat link which is improved in the foregoing respects. A particular object is to allow rapid mutual sliding telescoping movements of the links in the separating and gathering operations. Another particular object is to allow close gathering of the slats. Another particular object is to provide accurate spacing of the slats when they are separated. Another particular object is to firmly hold the lower ends of the slats when they are separated and spaced across the window opening. A further object is to avoid the use of any bulky, unsightly or otherwise objectionable mechanism incident to the foregoing operations and features thereof. Still another object is to insure continued smooth working in the manner indicated, regardless of influences such as atmospheric attack, unskilled handling and the like.

These objects have been achieved by a new slat link, preferably molded from high tensile strength synthetic plastics such as nylon, substantially consisting in four parts which are integral with one another and a fifth part vertically pivoted thereto. The integral parts are (1) a long horizontal bar of approximately rectangular cross-section, which serves as a guide and spacing element; (2) a hook vertically projecting from one end of the bar as a further spacing element; (3) a guide and stop unit at the opposite end of the bar, to cause easy sliding telescoping of interconnected bars; and (4) a pivot unit horizontally projecting from one side of the guide and stop unit to allow the pivoting of the slat carrier. In addition there is provided (5) as the separate pivoted unit, the slat carrier vertically pivoted to the pivot unit and holding the end of the slat.

For the control of the bottom ends of the vertical slats of each of the aforementioned units of parts 1, 2, 3 and 4 is directly, pivotally connected with the corresponding slat carrier 5 which holds the bottom end of the slat. The links formed in this manner form a telescoping chain which has practically full freedom of movement horizontally in the plane of the Venetian blind installation, and limited freedom of movement in other directions, as will be explained.

2

For the control of the top ends of the slats the units formed by parts 1, 2, 3 and 4 are desirably installed in upper parts of slide and tilt-controlling units of mechanism whereas the slat carriers 5 are installed in lower parts of such units of mechanism. The possibility of so using the component parts of the new link in direct conjunction with one another or with a control mechanism interposed is an additional feature and object of this invention.

10 The details of construction and operation will be understood as the specification proceeds. In the drawing:

Figure 1 is a diagrammatic front view of a small Venetian blind installation in accordance herewith, seen from the inside of the room, with the slats partly gathered.

Figure 2 is a section taken along lines 2—2 in Figure 1.

Figure 3 is an enlarged detail from the lower right hand corner of Figure 1.

Figure 4 is a view along lines 4—4 in Figure 3.

Figure 5 is a more enlarged front view of one of the 20 slat links according to this invention, utilized as a bottom control unit.

Figure 6 is a top view of the link of Figure 5.

Figure 7 is an end view of the link of Figure 5.

Figure 8 is a detail from the lower central part of 25 Figure 1 when the slats have been separated to cover the entire window opening and tensioned across the same.

The Venetian blind is substantially formed by a series of vertically elongated slats 10 having identical top and bottom ends 11 to fit the identical top and bottom slat carriers 12. For this purpose there may be formed a straight edge 13 slightly recessed within the top or bottom of each slat, so that a slat with smoothly formed and rounded corners 14 can be efficiently centered relative to a small carrier 12 hereinafter described.

30 The slats 10 on carriers 12 are suspended from a top mechanism 15 the details of which need not be described herein and which allows and properly controls both sliding movements of the slats in the plane of the Venetian blind installation, that is, parallel to the window 16, while also allowing and properly controlling tilting of the slats about vertical axes. The sliding of the slats, that is, their extension over the window opening or removal therefrom, is controlled by a pair of pull-cords 17 while the tilting of the slats, when extended across the window opening, is controlled by another pair of pull-cords 18. Incident to both operations the lower ends 45 of the slats are restrained and controlled by a chain 19 of links, formed of the lower slat carriers 12 and their corresponding telescoping slide-control units 20.

50 Slat carriers 12 and slide-control units 20 are also installed in the top installation 15, at the bottom and top respectively of sliding units 21 of the top mechanism. In the bottom mechanism 19 the units 12 and 20 are directly interconnected, for instance by a pivot pin 22 depending from the center of the bottom 23 of each slat carrier and journaled in a pivot unit or bearing 24 forming part of slide 20.

55 Each bearing 24 forms part of a guide and stop unit 25 at one end of the corresponding slide 20. The body of the slide 20 is substantially formed by a bar 26 horizontally elongated in the plane of the Venetian blind installation. A hook 27 extends vertically, in the case of the bottom control slides upwardly, from the end of the bar 26 opposite the guide and stop unit 25.

60 It is usual to make the slats 10 of Venetian blinds approximately 2 inches wide. It is therefore possible to obtain good results by making the effective telescoping length of each bar 26 for instance exactly 1 $\frac{1}{8}$ inches and the maximum distance between slat centers for instance exactly 1 $\frac{1}{8}$ inches. The cross-section of each bar is desirably slender and rectangular and measures $\frac{3}{16}$ inch vertically and $\frac{1}{32}$ to $\frac{1}{16}$ inch horizontally.

The limiting of the telescoping motions must be accurate and uniform. For this purpose each hook 27 has a suitably located, vertical abutment surface 28 facing the guide and stop unit 25 of the corresponding telescoping slide 20; and each guide and stop unit 25 has a similar surface 29 facing the hook 27 of the unit, this latter surface being formed in a suitable wall portion 30 of the guide and stop unit 25.

When the chain 19 is fully extended, so that the Venetian blind covers the window opening, all surfaces 28 and 29 are in contact with one another and the slats are uniformly spaced from one another, with their vertical edges slightly overlapping over one another when they are tilted for shading.

Tilting of the slats, in order to reduce or control the shading or to direct the light in predetermined directions, is allowed by the pivots 22, 24. The motive power for tilting is provided by operation of the tilt cords 18, the energy being transmitted to the individual slats in uniform manner by a tilting mechanism forming part of the top mechanism 15 and cooperating with each sliding top unit 21. A desirable mechanism for this purpose is described in my co-pending application Serial No. 385,118; briefly, it comprises a horizontal control rod, tiltable about a horizontal axis by a mechanism such as the pair of cords 18 and extending through the slidable mechanism units 21, among which there may be master slides for the control of the gathering and separating motion and follower slides on both sides of the Venetian blind installation. As to the tilting motion all slides of the top installation may be uniformly constructed, oriented and arranged. Each of them may form a small vertical channel transverse of the plane of the blind, having vertically slidable therein another channel member. Tilting of the horizontal tilt bar causes vertical sliding of the last mentioned channel member and this in turn causes tilting of another member about a vertical axis; the top slat carrier 12 of each unit 21 being attached to this last mentioned member. A helix and nut engagement has been found useful for the engagement between the slidable channel member and the last mentioned member and very uniform and accurate tilting motions can be obtained by the horizontal tilt-control bar as mentioned.

The sliding units of mechanism 21 are desirably held in proper downwardly facing orientation in a manner which is also disclosed in my co-pending application Ser. No. 385,118, and other provisions are desirably made as there described to insure suitable operation of the system of slats. The novel feature provided by the present invention may be identified with the new telescoping links, which take the place of the links 86 and 90 shown in the earlier application, while the bottom restraining mechanism 39, 40, 56, 57, 41 and 42 of the earlier application is entirely eliminated by the present construction.

Because of the elimination of the bottom slide-controlling bands or cables 41, 42 of the earlier application, the present system of slats reacts to rapid sliding by the pull-cords 17 in the manner of an ordinary curtain rather than in that of the earlier Venetian blind installation. This tendency has been a source of difficulty in earlier attempts to work with free-hanging slats, because of irregular mutual impingement between slats and connected problems. In the present installation such problems are avoided and in fact the performance of the slats is smoother than in those cases where attempts were made to positively control the motion of the bottom ends.

For instance it may be considered that initially, both halves of the Venetian blind installation are gathered on their respective sides of the window. In that condition the different bars 26 of the telescoping slides 20 rest substantially side by side, forming a solid pack the ends of which are slightly staggered. Because of this arrange-

ment relative mutual movement between the slats due to wind or the like is safely prevented in this condition.

Assuming now that the pull-cords 17 are operated to extend the Venetian blind across the window opening, this operation starts by causing a first top mechanism unit 21 to move towards the center. When it has moved a predetermined distance the connected hook 27 engages a second top mechanism 21, and so on, so that the top carriers 12 are started across the window one after the other. If this is done rapidly inertia will cause a slower following of the lower ends, so that temporarily some or all of the slats and mainly the leading ones will be slightly inclined in an approximate A shape in the plane of the window. On the opposite or gathering stroke, correspondingly, an approximate V shape may tend to be formed.

In order to allow such temporary inclination of slats, without binding of the telescoping slides 20, the guide and stop unit 25 of each slide has a channel 31 for the corresponding bar 26, which channel is formed by solid side walls 32, 33 and bottom wall 34 but substantially open at the top. Thus it is possible for the corresponding straight bar 26, sliding in the channel 31, to slide either in strictly horizontal directions or to rise or drop slightly, as the chain 19 follows the motion of the moving slats.

When the telescoping slides 20 are formed of high tensile strength synthetic resin such as nylon, by molding in suitable dies their surfaces can be made sufficiently smooth, and resistant to atmospheric attack and the like, to insure very free and easy telescoping or sliding in the motions described and suggested; likewise the operation of the telescoping slides themselves and of the slats connected therewith by the carriers 12 can be kept substantially noiseless and satisfactory in the various other respects which are known to the art and which were problematic in earlier installations.

When the slat installation 10, etc. has been extended across the window plane it is again desirable to avoid any substantial swinging of slats due to wind or the like. To a large extent this is achieved already by the interaction between the bars 26 and the channels 31 engaging the same. However, the links are desirably and necessarily small and flexible, and additional protection is desirable against substantial wind action. Therefore I prefer to use special inner and outer end links as shown respectively at 35 and 36. The inner end link 35 serves to interconnect the two innermost slat control bars 26 whereas a pair of outer end links 36 serves to anchor the outermost slats to the window frame 37. For this latter purpose an L-shaped bracket 38 is secured to a lower part of each vertical part or stile of the window frame, with a horizontal bracket extending therefrom in a direction parallel with the window. An outermost guide and stop unit 39, with a bearing for the outermost slat carrier 12 thereon, is directly swiveled to the underside of the bracket 38, and is connected with an outermost bar 40, having a hook 27, by a set screw 41. The expedient of so building up the outermost link 36 from a separate bar and hook unit 40, 27 and guide and bearing unit 39 has the advantage that the slat installation can be adapted to various window dimensions more readily than otherwise; in other words the overlap between the slat edges can be made non-standard at this point. Jointly, the end links 35 and 36 serve to form a taut chain 19 across the window opening when the inner end links 35 have been interconnected in any suitable manner, as by snap action or the like. The chain of links 20, 12 is then stretched from one bracket 38 to the other with sufficient tightness to hold the slats safely even against a strong wind.

This stretching, without disturbance of accurate slat spacing and without cumbersome spring mechanism or the like, is greatly facilitated by the use of plastic spacer bars 26, as described, which are slender and somewhat stretchable due to the horizontal narrowness of their cross-sec-

tional areas. At the same time these bars have proper resistance against compressive loads and bending loads in vertical planes, as required in the slat-gathering movements; this resistance being provided by the relative, vertical width of the cross-sectional areas of the bars. Mere wires as slat spacers, which have been tried, have been found much less satisfactory. They and their corresponding guide units became either too wide to allow close and compact gathering of slats and resilient stretching of the link chain across the window, or too thin to provide resistance against kinking and the like. The new bars and slat links avoid all of those defects.

The new links are also easy and cheap to make, by well-known plastic molding procedures. No machining or the like is required to make them ready for installation and use. They can be standardized completely as to size, design, material, color, etc.

The installation of the new links, with their slat carriers and slats, is equally simple. The process may start with the simple and obvious installation of a first link carrier and slat, adjacent the lower part of the window frame. The hook 27 of this first link is oriented so as to point approximately horizontally toward the inner part of the window plane. A second link unit is then connected with the first as follows. The second bar is held parallel to the window plane, with the hook so oriented as to point toward an inner, upper part of the plane. In such position, the channel of the second guide unit can easily be slipped over the hook of the first link; this being facilitated by making the lower corner or end portion 26-A of the bar, below the hook, in rounded form. The second link is then brought into approximately horizontal position as required for actual use, whereupon the connection between the first hook and the second channel cannot be resolved any more, due to engagement of the stop surfaces 28, 29. The second slat is then inserted in the second slat carrier, and successive links are added in the same manner. The procedure is substantially similar at the top.

Removal and replacement of any slat, for repair or the like, is similarly easy. Because of the high flexibility of the link chain 19 in a vertical plane, slat links adjacent the slat to be removed can be manipulated so that the slat to be removed or replaced can be slipped from or into the corresponding slat carrier, without bending and kinking of the slat.

In the practical, daily use, where the Venetian blind may be opened or closed by either slow or rapid manipulation of the pull-cords 17, the link chains 19 are extended

or collapsed smoothly and uniformly, link by link. When the chain has been extended the slats can be tilted as desired; when tilted parallel to the window plane they effect a practically perfect light seal, due to the absence of any end support or intermediate support that could disturb the strictly vertical orientation and straight form of the slat edges. While the slat edges when so tilted for a full light seal are in close contact with one another, rattling due to wind is effectively counteracted by the link chain

10 19, restraining adjacent pairs of slat ends from movement relative to one another.

Various modifications can be applied to the mechanism described, as will be obvious to persons skilled in the art upon study hereof.

I claim:

1. A one-piece slat link for connecting an end of each slat of a vertical Venetian blind with an end of another slat, comprising a single straight bar as long as the slats are to be spaced when the blind is fully extended, said bar being adapted to be confined to the vertical plane of the blind, the entire bar being rigid in such plane and resiliently flexible across such plane; a vertically projecting hook at one end of the bar; a guide and stop unit at the opposite end of the bar, having a guide channel area matching the cross section of a similar bar, to allow sliding of the bars relative to one another in said plane only, and adapted to stop such sliding at predetermined end points; and a pivot unit on the guide and stop unit, having a vertical axis for pivoting thereon a slat carrier; said bar, hook, guide and stop unit and pivot unit being formed of slightly resilient material, integrally with one another.

2. A slat link as described in claim 1 wherein the guide channel area of the guide and stop unit is shaped so as to allow substantial flexing of one link relative to the next in said vertical plane, without separation of the links incident to such flexing.

3. A slat link as described in claim 2 wherein the bar, adjacent the hook, has an end portion so rounded as to facilitate interconnection and separation of links, upon still further flexing of one link relative to the next in said vertical plane.
